UNITED STATES PATENT OFFICE.

WILLIAM WALKER STRONG, OF PITTSBURGH, AND ARTHUR FLEMING NESBIT, OF WILKINSBURG, PENNSYLVANIA, ASSIGNEES TO R. B. MELLON, OF PITTSBURGH, PENNSYLVANIA.

MEANS FOR REMOVING PARTICLES OF SUSPENDED MATTER FROM BODIES OF FLUID AND THE LIKE.

1,117,531.

Specification of Letters Patent.

Patented Nov. 17, 1914.

Application filed February 11, 1913. Serial No. 747,784.

To all whom it may concern:

Be it known that we, WILLIAM WALKER STRONG and ARTHUR FLEMING NESBIT, citizens of the United States, residing at Pittsburgh and Wilkinsburg, respectively, in the county of Allegheny and State of Pennsylvania, have invented new and useful Improvements in Means for Removing Particles of Suspended Matter from Bodies of Fluid and the like, of which the following is a specification.

This invention contemplates certain new and useful improvements in means for removing particles of suspended matter from bodies of fluid and the like, by the application of electrical discharges to the said bodies.

Heretofore electrical discharges have been employed for the purpose of removing suspended matter from fluids, etc., which discharges may consist of brush discharges, the electrical wind, the corona discharge, etc. The nature of these discharges is not well known, but they involve among other phenomena, secondary ionization of the fluid medium, which may be due to the collision of the ions with the fluid particles, or it may be due to electromagnetic pulses or waves. It is known, however, that electrical discharges of this kind result in a copious production of ions. Any discharge can be effected only by the use of one or more electrodes placed in or near the fluid medium, and the electrical discharge may be caused to take place from one electrode, which is designated as the active electrode. In the art of removing matter from fluids, the electric field may be made very concentrated near the active electrode in order that the luminous, heat and ionization effects may be localized in the neighborhood of the said electrode. The secondary ionization produced in this region results in the production of a large number of positive and negative ions. The ions having charges similar to that of the active electrode are attracted toward it and are said to give up their charge to this electrode as ions of the said sign of charge. Ions possessing a sign of charge that is the same as that of the active electrode are repelled from it and if the secondary ionization is sufficiently intense and continuous, this flow of ions will be designated as a stream of ions, or an electric current.

The object of the present invention is to utilize these phenomena in removing suspended matter from fluids, etc., by passing the latter between an active and a grounded electrode, the latter being shaped to secure the desired results.

A further object is to produce a separating apparatus which is particularly adapted for use in tunnels and the like.

The invention will be hereinafter fully set forth and particularly pointed out in the claims.

In the accompanying drawing:—Figure 1 is a transverse sectional view of a separating apparatus embodying our invention, the electric circuit, source of energy, etc., being illustrated diagrammatically. Fig. 2 in a side view with a simple electrical circuit shown. Fig. 3 is a transverse sectional view of a modification of Fig. 1. Fig. 4 is a similar view of another modification. Fig. 5 is a diagrammatic view illustrating another modified form of separating cell. Figs. 6, 7 and 8 are diagrammatic views illustrating the action of the electrode.

We wish to have it understood that our electrical circuits are made up of such combinations of series and parallel groupings of resistances, inductances, capacities and spark gaps and with or without a current rectifying device as will best accomplish the work to be done.

Referring to the drawing, 10 designates a generator of any suitable or preferred type, and 11 the primary low potential coil of a transformer 12. The high potential coil 14 of the transformer may be connected as shown in the figures with a suitable rectifying device 15, the same being utilized for maintaining the potential of the active electrodes 16 unipolar. It will be understood, however, that we do not desire to limit ourselves to the use of a unidirectional current, or to the use of a rectifier, although we prefer to use the same. In Fig. 1 the grounded electrode is illustrated as formed of oppositely disposed members 17, 18 placed one above the other, and each formed with lateral branches 19 extending in opposite directions, said lateral branches being also curved downwardly. Each member 17, 18, is provided with a plurality of spaced apart bulged portions 20 connected by intermediate straight walls

21, said bulged portions and connecting walls coöperating to form a plurality of approximately cylindrical cells connected by constricted passage ways, the active electrodes 16 being centrally disposed in said cells. It will be noted that the member 17 is provided with spaced apart parallel walls 22 forming an entrance conduit for the separating apparatus, the member 18 being provided with two of the bulged portions 20 immediately over the top of said conduit. We do not desire to be limited in this particular, however.

In operation, the plates or walls 22 extend low enough for the smoke stack of a locomotive or the like to pass between them, the grounded electrode or separating device being secured to the ceiling of a tunnel, or the like. As the smoke emitted by said stack 15 enters the conduit 22 it passes laterally to both sides and successively through the various cells 20 and constricted passages until discharged at the outlet ends of the grounded electrode. In their passage through the 20 space between the members 17, 18, the suspended particles will fall upon said member 17 from whence they may be removed in any suitable or preferred manner. If desired, the bottom wall 17 may be omitted, as illustrated in Fig. 3 in which event the suspended particles are attracted to the upper electrode or member 18. Or said member 17 may be made of wire net or gauze as indicated in Fig. 4 at 17'. In lieu of forming 25 the separating cells in the manner shown and described above, the same may be made in the form of a frustum of a cone, as illustrated at 23, Fig. 5. The purpose of providing the grounded electrode with oppositely extending passageways or arms is to provide a symmetrical form of precipitator 30 adapted to fit into the arch of a conduit or tunnel, and at the same time expose a large amount of grounded surface to the active electrode.

In practice, irrespective of what the direction of travel may be the fluids subjected to the ionic currents are wholly or partly cleaned of their solid and liquid matters held 35 in suspension, the latter being deposited upon the inside surface of the grounded electrodes. When sufficient matter has been deposited upon these surfaces to provide for a gap for a disruptive discharge to pass, sparking 40 takes place, and this causes more or less of the precipitated matter to be loosened from the electrode. The portions of the deposited matter thus loosened fall down through the cell. In this method of cleaning 45 the electrodes it is necessary to have certain predetermined relations between the capacity, self-induction, and resistance factors of the high tension circuit so that the discharge is disruptive when the distance between the electrode 16 and the deposited

matter is less than the disruptive potential of the body carrying the suspended particles.

For the purpose of producing disruptive or oscillatory discharges various suitable 70 conditions may be imposed upon the electrical circuits connected to the active and grounded systems of electrodes. For the purpose of illustration, beside the resistance, capacity, and self induction of the transformer itself, we have shown in Fig. 2 certain combinations of resistances 24, 25, capacities 26, 27, self-inductances 28, 29 and spark gaps 30, 31, distributed in the secondary circuit, so that under working conditions 75 electromagnetic oscillations of the proper frequency and damping factor are produced. These resistances, capacities, self-inductances and spark gaps are placed in whatever parts of the circuit found most suitable 80 or desirable for the results desired, and for obvious reasons we do not limit ourselves to the precise arrangement illustrated. Among other conditions may be included the use of a number of phases of current or electromotive force; the frequency of these phases 85 may have any suitable value and need not be of the same value. Thus one phase may have the value of its capacity, self inductance and resistance such that a discharge 90 due to this phase would be disruptive or oscillatory in nature, while the discharges of the other phases could be of a flammable or arc-like character. The impression of these electromotive forces and current waves 95 need not be simultaneous and may be effected by independent electrical circuits. In a like manner the phase relation between the current and electromotive force waves of any 100 circuit may be regulated so as to produce disruptive or oscillatory discharges, and by this means effect the removal of matter contained in the fluids subjected to the action of the electrodes. It is obvious, however, 105 that the deposited matter may be removed 110 from the electrodes in any other suitable manner, for instance by causing the latter to vibrate under the stroke of a hammer or the like, whereby the adhering particles are dislodged.

It has been found experimentally that when precipitating the so-called smoke from soft coal furnaces, there is considerable ash and tar carried along with the soot (or carbon) and on account of the high temperature 115 of these ingredients, more or less adheres to the central or active electrode and also to the inner walls of the grounded electrode. The actual conditions which have been met may be illustrated by reference to 120 Figs. 6, 7, and 8. In Fig. 6 the active electrode 16 is shown as having a deposit, which for the sake of illustration may be taken as about $\frac{1}{8}$ of an inch in radial depth at the position *a* and at the positions *b* and *c* some- 125

what less. As soon as the distance at the point *a* between the electrode 17 and the deposited matter has been reduced by accumulations upon the electrode 16, to such a value 5 that a disruptive discharge takes place, a momentary spark passes, and simultaneously with the occurrence of this spark the deposit on the actual electrode between the planes *x* and *y* and *u*, *v*, is violently dislodged and settles into the chamber below. (See Fig. 7). At the same time a large 10 patch of the comparatively thin deposit on the inner wall of the grounded electrode would become detached from the latter and breaking into small pieces also fall into the deposition chamber. The next disruptive 15 discharge would in all probability take place in succession at such positions as *b* and *c* respectively. It has been our experience that such deposit might accumulate 20 once in an hour, with very tarry smoke, and within perhaps a minute or two, the active electrode 16, throughout its entire length would have dislodged the deposit that had 25 formed upon it. It has also been observed that the corona formation remains remarkably uniform, radially about the entire length of the active electrode, even though the radial depth of the deposit may vary as 30 suggested in Fig. 6. At the points where the disruptive discharge is about to take place, the greater radial depth of the deposit tends to thin out the corona glow as observed by the eye, and at the same time 35 causes no apparent diminution of the corona elsewhere along the electrode 16.

The peculiar property possessed by an electric arc, that the potential difference across its terminals increases as the current 40 through it decreases, may be utilized to produce electric oscillation.

The grounded electrode 17 is shown to be the collecting electrode, in the drawing, the object of making it such being to minimize the amount of insulation necessary for the bulky parts of the electrodes and at the 45 same time properly control the flow of gases, etc., which may be admitted. The electrode 16 is called the active electrode because the 50 electric field and consequent ionization is most intense at the surface of this electrode.

Having thus explained the nature of our invention, and described an operative manner of constructing and using the same, although without attempting to set forth all 55 of the forms in which it may be made, or all of the forms of its use, what we claim is:—

1. An improvement in means for removing suspended matter from bodies of fluid and the like, comprising a grounded electrode having oppositely extended passage ways for said bodies, active electrodes ar-

ranged in juxtaposition to said grounded electrode, and means for maintaining said 65 electrodes at a high difference of potential.

2. An improvement in means for removing suspended matter from bodies of fluid and the like, comprising a grounded electrode having oppositely extended arms each 70 provided with spaced apart bulging portions connected by intermediate walls, active electrodes disposed opposite said bulging portions, and means for maintaining said electrodes at a high difference of po- 75 tential.

3. An improvement in means for removing suspended matter from bodies of fluid and the like, comprising a grounded electrode having oppositely extended arms each 80 provided with a plurality of cells connected by passage ways, active electrodes in said cells, and means for maintaining said electrodes at a high difference of potential.

4. An improvement in means for removing suspended matter from bodies of fluid and the like, comprising a grounded electrode having oppositely extended arms each 85 provided with a plurality of cells connected by tapering passage ways, active electrodes 90 in said cells, and means for maintaining said electrodes at a high difference of potential.

5. An improvement in means for removing suspended matter from bodies of fluid and the like, comprising a grounded electrode having an inlet passage and oppositely extended lateral discharge members 95 communicating with said passage, active electrodes extending into said grounded electrode, and means for maintaining said 100 electrodes at a high difference of potential.

6. An improvement in means for removing suspended matter from bodies of fluid and the like, comprising a grounded electrode having oppositely extended arms and 105 an inlet between said arms, active electrodes passing through said arms, and means for maintaining said electrodes at a high difference of potential.

7. An improvement in means for removing suspended matter from bodies of fluid and the like, comprising a grounded electrode having oppositely extended arms and depending plates, the latter forming an inlet passage, active electrodes passed through 110 said arms, and means for maintaining a high difference of potential between said electrodes. 115

In testimony whereof we have hereunto set our hands in presence of two subscribing 120 witnesses.
